E. F. SHERRICK

CIRCULATOR FOR WELLS

Filed Jan. 4, 1926

UNITED STATES PATENT OFFICE.

EDWARD F. SHERRICK, OF LOS ANGELES, CALIFORNIA, ASSIGNOR OF THIRTY-THREE AND ONE-THIRD PER CENT TO FRANK C. WISER AND THIRTY-THREE AND ONE-THIRD PER CENT TO THOMAS E. McLAUGHLIN, BOTH OF LOS ANGELES, CALIFORNIA.

CIRCULATOR FOR WELLS.

Application filed January 4, 1926. Serial No. 79,131.

This invention has to do with devices and systems for flowing fluid from a well by fluid circulation. Systems in which oil or water is raised from a well by introducing either gaseous or liquid fluid under pressure have been well known and are now in use. Such systems may use either gas or liquid as a moving fluid. My device is applicable to the use of either kind of fluid and is not limited necessarily to the use of a liquid as a moving fluid; but because the device in its present form has been designed particularly for using liquid as a moving fluid I shall describe it is used in that manner, but without thereby necessarily limiting the invention to such use.

As applied particularly to oil wells, devices of the kind herein described have utilized two balanced columns of liquid, one column being put under a slight additional pressure to force the flow through an injector nozzle and thereby to maintain upward movement in the other column to raise the oil to the surface. I have found in the use of such devices that there is a very prevalent tendency for the nozzles to clog up, particularly if the oil carries any substantial amount of foreign matter, as many oils do. Also as heretofore constructed such devices have been rather difficult to place in a well and to remove for cleaning, repair or renewal. It is among the objects of my invention to provide a form of device that can be easily placed and removed, and that can be operated in such a manner as to easily clean itself of any clogging material without the necessity of removing the device completely from the well. How these and other objects of the invention are accomplished will be best understood from a consideration of the following detailed specification, wherein I describe a preferred and illustrative form of device embodying the invention, reference for this purpose being had to the accompanying drawings, in which:

Fig. 1 is a longitudinal vertical section of a well, showing, in elevation, my device installed therein;

Fig. 2 is an enlarged longitudinal section of my device in place in a well casing;

Fig. 3 is a cross section on line 3—3 of Fig. 2;

Fig. 4 is a cross section on line 4—4 of Fig. 2;

Fig. 5 is a cross section on line 5—5 of Fig. 2; and

Fig. 6 is a longitudinal section of certain parts shown in Fig. 2, showing those parts in the position they assume when the device is operated for self-closing.

There is shown in the drawing a well casing or other well pipe 10 within which a tubing 11 extends from the surface to a point either below the normal oil level or in proximity thereto. The upwardly flowing column of oil from a well flows up and out through tubing 11; the balancing column of oil that flows downwardly is in the annular space between tubing 11 and casing 10.

At the lower end of tubing 11 I attach a barrel 12 having through its walls suitable openings 13 through which the liquid may flow from the outer column into the inner column. Inside barrel 12 and in communication with openings 13 is an annular groove 14 to form communications with openings 15 in member 16 in case member 16 is so placed that openings 15 do not register with openings 13. Member 16 I shall term the outer nozzle member. An inner nozzle member 17 seats at its lower end on a conical set 18 formed in barrel 12. This inner nozzle member has a central bore 19 extending vertically through it, and has an upper reduced part 20 that terminates at its upper end in a conical tip 21, all as is best shown in Fig. 2. This conical tip stands concentrically inside an upwardly tapered bore 22 of outer nozzle member 16, the conical tip and tapered bore 22 together forming between them an annular conical nozzle space that tapers in form and also decreases in cross sectional area as it proceeds upwardly. All this will best be seen by inspection of Figs. 2 and 4.

This conical nozzle space designated 23 on the drawing delivers at its upper end into bore 24 of nozzle member 16; and from this bore 24 the upwardly moving stream of liquid is delivered directly through the open cage bars 25 of member 16 into tubing 11 above. Cage bars 25 form the mechanical

means of connection of member 16 with head 26 into which the lifting rod 27 is screwed, this rod extending to the top of the well and forming a means by which the 5 whole device may be inserted in or lifted from the well without the necessity of removing tubing 11.

When the device is in place for operation the parts occupy the relative positions 10 shown in Fig. 2, with the lower annular edge 16^a of nozzle member 16 resting on the upwardly facing shoulder 17^a of nozzle member 17. Nozzle member 16 is held in position merely by so resting on member 17 15 and by the weight of rods 27 upon it. It has been found in practice that the weight of a comparatively short length of rods is sufficient to keep nozzle member 16 down in operative position against the upward 20 pressure exerted upon it by the flowing fluid.

Also attached to head 26 and depending therefrom is a combined lifting rod and guide member 30 which extends down 25 through bore 24 of member 16 and bore 19 of member 17 and preferably has longitudinal ribs 31 engaging bore 19 so as to accurately center the upper conical tip of member 17. Member 17 is, of course, centered by the fit of its lower end in barrel 12 and by its seat at 18; but to insure concentricity of its upper end with nozzle member 16, I provide the centering member 30 with its ribs 31. Member 30 extends on 30 down below the centering ribs 31 in the form of a rod 30^a for the purpose of carrying and pulling the standing valve 35. This standing valve may be of any usual type and has a tube 36 attached to its head, this 35 tube having at its upper end an internal bushing 37 against which head 30^b of rod 30^a moves upwardly when the whole device is pulled from the well. Standing valve 35 seats in the usual seat member 38 and 40 the valve itself may carry an inner suction tube 39 that depends into the oil below. This structure and arrangement, however, are well known. The normal distance between head 30^b and bushing 37 is sufficient 45 that the standing valve is not raised until rod 30^a and the parts attached to it have been raised a little distance. It is by raising these parts that the device is put into position to have the nozzle cleaned out of 50 any obstructing matter; and it is desirable to be able to raise the parts for cleaning without necessarily raising the standing valve. The function of the standing valve is merely to keep the column of oil from 55 flowing downwardly in case of stoppage of circulating operations; and by keeping it always on its seat during a cleaning operation the height of the column raised in the tubing is not lost each time.

60 In operation, as for pumping oil from an

oil well, crude oil (preferably the same oil that is being pumped from the well) is pumped down into the annular space between casing 10 and tubing 11, a communicating pipe 40 being shown in Fig. 1 for 70 this purpose. The space between the tubing and casing is thus filled with oil. A packer 41 placed between the tubing and casing at any point below openings 13, prevents the outer column of oil flowing on down into the lower part of the well and forces the oil in that column to flow through the openings 13 and through the described nozzle. The device as a whole is placed in the well 75 in such relation to the normal oil level 80 therein that the nozzle is either below the normal oil level or at least is in reasonable suction distance of the oil level. Typically the device as a whole would be below the normal oil level so that oil from the 85 lower part of the well will pass up through the standing valve, and passing up through bores 19 and 24, will stand above the nozzle. As a column of oil outside tubing 11 is created at a height greater than the height 90 of the column standing in tube 11, oil will flow inwardly through openings 13, etc., and flow upwardly through nozzle 23. It will be noted that this nozzle 23 is so arranged 95 with relation to the upper end of bore 19 that the upwardly flowing stream through nozzle 23 has an injector action with relation to oil standing directly above it, and therefore draws oil up through bore 19, 100 and sets in upward motion the whole column of oil above the nozzle. It will be noted that rod 30 concentrates the oil flow in bore 19 near the periphery and close to the stream flowing up through nozzle 23. If the center 105 of the bore were open the heavy oil pressure from above might set up a downward flow on the bore axis, passing oil down through the bore as fast as it were pulled up by the injector action. As the exterior oil 110 column is increased in height the interior oil 115 column is also increased in height; and when the exterior oil column has reached the top of the well, then additional pressure is put upon that column so that, when the interior 120 column reaches the top of the well, the pressure on the exterior column will still be sufficient to force oil upwardly through the nozzle and continue the injector action that keeps the inner column in constant upward motion. The pressure necessary for this 125 purpose on the outer column is comparatively small; even in a deep well with comparatively heavy oil a pressure of 20 pounds per square inch will keep the columns in motion. It will be understood, of course, 130 that liquid must constantly be pumped in at the top of the outer column; but that the volume of liquid raised in the inner column is many times more than the volume pumped into the outer column.

The device will operate constantly subject only to an occasional clogging of the nozzle. When this occurs in my device it is only necessary to lift rods 27 a short distance so as to lift the outer nozzle member 16 to some such position as illustrated in Fig. 6, opening up the nozzle 23 and allowing the upward flow of liquid to clean out the obstruction. This can be done without stopping the circulation at all; then the parts immediately lowered to operating position. It will be noted that when the outer nozzle member is thus slightly lifted the standing valve is not disturbed, and neither is the lower nozzle member 17 disturbed, as the standing valve is only picked up after the rods have been moved up a much larger distance; and the lower nozzle member 17 is not picked up until the standing valve has been picked up and the upper end of bushing 37 is carried up against lower member 17. However, when it is desired for any reason to remove the device from a well it is easily done by merely pulling the rod, when the whole device is moved at once without any necessity of disturbing the tubing. And for facilitating removal and replacement it will be noted that the smallest internal diameter of barrel 12 is amply large to pass the standing valve and also that all the parts of the nozzle device itself fit the barrel with a fairly easy fit. Both nozzle members 16 and 17 are made to fit the barrel fairly snugly and yet be freely slideable in the barrel so as to be easily placed and removed. The internal bore of the barrel is itself somewhat smaller than the diameter of tubing 11.

I claim:

1. A device for pumping wells by fluid circulation, embodying a barrel adapted to be connected with a well tubing, the barrel having openings through its wall and an internal seat below said openings, an inner and lower nozzle member seated on said seat, an upper and outer nozzle member arranged above and surrounding the first mentioned nozzle member and forming therewith an upwardly discharging nozzle communicating at its lower end with said openings, both said nozzle members being removable from the barrel by upward movement, a lifting rod attached to the second mentioned nozzle member and means attached to said second mentioned nozzle member and adapted to engage and lift the first mentioned nozzle member when the second mentioned nozzle member has been lifted a predetermined distance.

2. A device for pumping wells by fluid circulation, embodying a barrel adapted to be connected with a well tubing, the barrel having openings through its wall and an internal seat below said openings, an inner and lower nozzle member seated on said seat,

an upper and outer nozzle member arranged above and surrounding the first mentioned nozzle member and forming therewith an upwardly discharging nozzle communicating at its lower end with said openings, both said nozzle members being removable from the barrel by upward movement, a lifting rod attached to the second mentioned member and adapted to engage and lift the first mentioned nozzle member when the second mentioned nozzle member has been lifted a predetermined distance, said nozzle members forming an upwardly converging conical nozzle, so that lifting of the upper and outer nozzle member will open up said nozzle as and for the purpose described.

3. A device for pumping wells by fluid circulation, embodying a barrel adapted to be connected with a well tubing, the barrel having openings through its wall and an internal seat below said openings, an inner and lower nozzle member seated on said seat, said nozzle member having a reduced upward extension at a point opposite said openings, and said upward extension having an upwardly tapering conical nozzle tip, an upper and outer nozzle member normally resting at its lower edge on the first mentioned nozzle member and having an upwardly tapering conical bore which in its normal position spacedly surrounds the tapered nozzle tip of the first mentioned member to form an upwardly tapering annular nozzle, said last mentioned nozzle member having openings at points opposite the openings through the barrel so that fluid may flow from outside the barrel to the lower end of said nozzle, and the last mentioned nozzle member also having a bore leading upwardly from the nozzle, a cage head on the last mentioned nozzle member, lifting rods attached to said head and a rod attached to and depending from said head and provided with means for lifting the lower nozzle member after the upper nozzle member has been lifted a predetermined distance.

4. A device for pumping wells by fluid circulation, embodying a barrel adapted to be connected with a well tubing, the barrel having openings through its wall and an internal seat below said openings, an inner and lower nozzle member seated on said seat, said nozzle member having a reduced upward extension at a point opposite said openings, and said upward extension having an upwardly tapering conical nozzle tip, an upper and outer nozzle member normally resting at its lower edge on the first mentioned nozzle member and having an upwardly tapering conical bore which in its normal position spacedly surrounds the tapered nozzle tip of the first mentioned member to form an upwardly tapering annular nozzle, said last mentioned nozzle member having openings

- at points opposite the openings through the barrel so that fluid may flow from outside the barrel to the lower end of said nozzle, and the last mentioned nozzle member also 5 having a bore leading upwardly from the nozzle, a cage head on the last mentioned nozzle member, lifting rods attached to said head, said lower nozzle member having a vertical central bore extending through it, and 10 a rod attached to and depending from said head and extending down through the bore in the lower nozzle member and provided with means to engage the under side of the lower nozzle member when the upper nozzle member has been lifted a predetermined distance, said rod also having longitudinal ribs 15 engaging the bore of the lower nozzle member at its upper end to center the upper end of said nozzle member.
- 20 5. A device for pumping wells by fluid circulation, embodying a barrel adapted to be connected with a well tubing, the barrel having openings through its wall and an internal seat below said openings, an inner 25 and lower nozzle member seated on said seat, an upper and outer nozzle member arranged above and surrounding the first mentioned nozzle member and forming therewith an upwardly discharging nozzle communicating at its lower end with said openings, both said nozzle members being removable from the barrel by upward movement, a lifting rod attached to the second mentioned nozzle member and means attached to 30 said second mentioned nozzle member and adapted to engage and lift the first mentioned nozzle member when the second mentioned nozzle member has been lifted a predetermined distance, and a standing valve arranged below 35 said valve and liftable by said last mentioned means after the upper nozzle member has been lifted a predetermined distance.
- 40 6. A device for pumping wells by fluid circulation, embodying a barrel adapted to be connected with a well tubing, the barrel having openings through its wall and an internal seat below said openings, an inner 45 and lower nozzle member seated on said seat, 50 said nozzle member having a reduced upward extension at a point opposite said openings, and said upward extension having an upwardly tapering conical nozzle tip, an upper and outer nozzle member normally 55 resting at its lower edge on the first mentioned nozzle member and having an upwardly tapering conical bore which in its normal position spacedly surrounds the 60 tapered nozzle tip of the first mentioned member to form an upwardly tapering annular nozzle, said last mentioned nozzle member having openings at points opposite the openings through the barrel so that fluid 65 may flow from outside the barrel to the lower end of said nozzle, and the last mentioned nozzle member also having a bore leading upwardly from the nozzle, a cage 70 head on the last mentioned nozzle member, lifting rods attached to said head, said lower nozzle member having a vertical central bore extending through it, and a rod attached to 75 and depending from said head and extending down through the bore in the lower nozzle member and provided with means to engage the under side of the lower nozzle member when the upper nozzle member has been lifted a predetermined distance, said rod also having longitudinal ribs 80 engaging the bore of the lower nozzle member at its upper end to center the upper end of said nozzle member, and a standing valve arranged below the barrel and liftable by said last mentioned rod after the upper nozzle member 85 has been lifted a predetermined distance.
- In witness that I claim the foregoing I have hereunto subscribed my name this 10 day of December, 1925.
- EDWARD F. SHERRICK.
